UNITED STATES PATENT OFFICE.

OSKAR KYLIN, OF ELKHART, INDIANA.

DEVICE FOR SHARPENING REAMERS.

Application filed July 26, 1924. Serial No. 728,333.

This invention relates to reamers, but more especially to devices for sharpening the blades of adjustable reamers.

The principal object of my invention is to provide a simple and cheap device for sharpening adjustable reamer blades, one which may be readily adjusted to carry reamers of various sizes.

Other objects of my invention are mentioned and described herein.

The preferred embodiment of my invention is illustrated in the accompanying drawing, in which Figure 1 is a side elevational view of a reamer sharpening device showing a reamer applied thereto; Fig. 2 is a top plan view thereof; Fig. 3 is a section taken on line 3-3 of Fig. 2; Fig. 4 is a fragment in elevation of the post carrying the reamer detent means, partially in section; and Fig. 5 is a top plan view of the hone carrier.

Similar numerals of reference indicate like parts throughout the several views on the drawing.

Referring to the details of the drawing, the numeral 1 indicates the main frame of the device which is provided with the opposed upstanding end bearing brackets 2 and 3, preferably cast in one piece, the latter being adapted to carry the adjustable pointed reamer supporting shafts 4 and 5 disposed axially of each other and adapted to support the reamer 6 in position while the blades of the latter are being sharpened.

The bracket 2 may be bored smooth at 7 to enable slidable adjustment of the shaft 4 therein, to enable reamers of various lengths to be mounted in the device, and said bracket may be split longitudinally at 8 at one side thereof and provided with a clamping screw 9 to enable the box 2 to be clamped about the shaft 4 to maintain the adjustment of the latter. The shaft 5 is preferably screw threaded into the bearing box bore 10 of box 3 and is provided with a knurled head 11 to enable fine adjustment of said shaft. The box 3 may be split at 12 similar to box 2 and provided with a clamping screw 13 to rigidly clamp shaft 5 in the bore 10. The shafts 4 and 5 are provided with conical points adapted to engage in suitable recesses in the ends of the reamer 6, the lat-

ter being provided with a plurality of blades 14 adjustably mounted therein, as is well known.

The frame element 1 may be provided at one side thereof with a pair of integral spaced brackets 15 and 16 which are suitably axially apertured to receive and carry the hone bracket bearing shaft 17 therein, 55 said shaft being held against longitudinal displacement by pins 18 and 19 mounted therein adjacent said brackets 16 and 15, respectively. The shaft 17 may have an extension 20 projecting beyond the bracket 16 60 for the hereinafter mentioned purpose. The numeral 21 indicates the hone carrier bracket or arm supported by the shaft 17, the latter engaging loosely in a suitable bore formed in the hub 22 of said arm to enable the 70 latter to be slidably adjusted to various positions between the brackets 16 and 17. A set or thumb screw 23 mounted in the arm hub 22 and adapted to be set against the shaft 17 prevents casual longitudinal movement of the arm 21 on said shaft, and a thumb screw 24 threaded into and through a lug 25 projecting downwardly from the arm hub 22, the point whereof engages the exterior of the frame 1, is adapted to prevent 75 downward oscillatory movement of the arm 21, and means whereby rotary adjustment of said arm may be effected.

The arm 21 is arranged at substantially right angles to the reamer 6 and the axis of the shafts 4 and 5 and the outer end thereof is provided with a pair of spaced upwardly projecting lugs 26, 26 adapted to form a guideway for the guide bar 28 projecting from the end of the hone carrier 29, the latter being adapted to have any suitable flat hone 30 detachably mounted therein in any suitable manner, as by set screws 31. The hone 30 is carried on the under side of the carrier 29 and is adapted to rest upon the cutting edge of a reamer blade 14 and the carrier bar 28 is arranged between the lugs 26, as specified, whereby manual reciprocatory movement of the carrier 29 and hone 30 may be effected transversely of and upon 85 the cutting edge of a reamer blade to sharpen the latter. The lugs 26 of the arm 21 are substantially spaced to permit lateral movement of the bar 28 and thereby the carrier 90 95 100

29, whereby the hone may be moved along the face of the blade, within predetermined limits, without adjustment of the arm 21 along the shaft 17.

5 The numeral 32 indicates a detent plate adjustably mounted in the post 33 transversely of the reamer 6, said plate being formed preferably of spring metal and adapted to engage the side of a reamer blade 10 14 to prevent rotary movement of said reamer when the hone 30 is in operation and for establishing the proper relation between the face of the hone and the cutting edge of the reamer blade. The post 33 is carried in 15 a socket or bore vertically formed in a boss 35 projecting from and integral with the frame 1 at one side thereof, said post being vertically movable in bore 34 and may be maintained in adjustment therein by a set 20 screw 36. The boss 35 may be provided with a second post socket 37, which may be a duplicate of socket 34, to enable the post 33 to be transferred thereto when it may be necessary or advisable to place the point of 25 the detent plate 32 to bear against the opposite end of a reamer blade, in which said socket said post may be vertically adjusted and held in adjustment by a set screw 38 corresponding with screw 36. The head or 30 top end of the post 33 may be transversely slotted at 38 to receive the plate 32 and a cap 39 may be secured or clamped over and against said plate by a cap screw 40 threaded through said cap into said post head.

35 In the operation of my improved device the reamer 6 is secured between the carrier pins 4 and 5 by adjusting the latter, as described, into engagement with the recessed ends of the reamer body. Thereafter, the 40 cutting edge of a reamer blade 14 is brought into proper relation with the flat face of the hone 30 and the detent plate 32 is then adjusted to snugly engage the side of said blade to prevent rotation of the reamer toward the post 33. Thereupon, the operator 45 grasps the reamer 6 with one hand and reciprocally operates the hone 30 in contact with the cutting edge of the reamer blade with the other hand, effecting longitudinal 50 adjustment of the arm 21, as described, to hone said blade throughout its length. When a second or subsequent blade is to be sharpened the reamer is reversely rotated manually to bring said blade into the 55 proper position, the detent plate 32 springing into position, ratchet like, without further adjustment thereof.

When a reamer, having blades of unusual length, must be sharpened the arm 21 may

be transferred from between the lugs 15 and 60 16 to the extension 20 of shaft 17.

I claim:

1. A reamer honing device comprising a frame, means for maintaining a reamer in a substantially horizontal position in said 65 frame, a stationary arm support arranged parallel with said frame and laterally thereof, an oscillatory arm mounted upon said support and adjustable longitudinally thereof and independently of said frame, 70 said arm being arranged laterally of the reamer, a hone carrier supported by said arm, a boss carried by said frame and provided with a plurality of upright sockets, a post adapted for selective mounting in said 75 boss sockets and vertically adjustable therein, and a reamer detent element adjustably mounted upon said post.

2. A reamer honing device comprising a frame, means for maintaining a reamer in a 80 substantially horizontal position in said frame, a stationary arm support arranged parallel with said frame and laterally thereof, an oscillatory arm mounted upon said support and adjustable longitudinally thereof and independently of said frame, 85 said arm extending laterally of the reamer, a hone carrier supported by said arm, a boss carried by said frame and provided with a plurality of upright sockets, a post adapted for selective 90 mounting in said frame boss sockets and vertically adjustable therein, the top end of said post being provided with a transverse slot; and a reamer detent element secured in said post slot.

3. A reamer-honing device comprising in combination, a frame provided with an integral boss on one side and a post-socket in said boss, the opposite side of said frame being provided with a plurality of integral 100 brackets; means for maintaining a reamer in a substantially horizontal position in said frame; a shaft mounted in said frame brackets substantially parallel with said frame; an oscillatory arm mounted upon 105 said shaft and adjustable longitudinally thereon and independently of said frame, said arm being arranged laterally of the reamer; a hone carrier supported by said arm; a post arranged in said post-socket and vertically adjustable therein; a reamer detent element mounted upon said post; and means for adjusting said detent element, said means including a cap detachably secured to said post.

In witness whereof I have hereunto affixed my signature this 23d day of July, 1924.

OSKAR KYLIN.
